Patented June 27, 1922.

UNITED STATES PATENT OFFICE.

FREDERICK L. LINDBORST, OF DETROIT, MICHIGAN, ASSIGNOR TO DETROIT TORCH & MANUFACTURING COMPANY, OF DETROIT, MICHIGAN, A CORPORATION OF MICHIGAN.

BURNER.

1,420,850.

Specification of Letters Patent. Patented June 27, 1922.

Application filed May 25, 1921. Serial No. 472,492.

To all whom it may concern:

Be it known that I, FREDERICK L. LINDBORST, a citizen of the United States, residing at Detroit, in the county of Wayne and 5 State of Michigan, have invented certain new and useful Improvements in Burners, of which the following is a specification.

This invention relates to burners for fire pots and blow torches. It is the object of 10 the invention to afford a burner arranged to give a flame which can be used where a broad, thin flame is desired, such, for instance, as used in a blow torch for removing paint from a house. Burners for giving 15 such a flame are not broadly new. These burners, however, have usually been heretofore made with the generating element and the nozzle in the top plate and a deflector and flame-spreading element suspended un- 20 der the generating plate. The present burner involves a number of novel features in the way of improved construction to give better results and afford a better article for economical production. This burner may be 25 supported upon a torch tank by a stem which screws into a nipple directly under the burner in place of supporting the burner at the side of the burner as is the case with the 30 type of burner having the generating element in the top plate.

In the drawings,—

Fig. 1 is a side elevation of the burner attached to a blow torch tank.

Fig. 2 is a plan view of the burner.

Fig. 3 is a vertical longitudinal section of the burner.

Fig. 4 is a vertical cross section of the burner.

Fig. 5 is a plan view of the lower part of 40 the burner.

The burner is formed by a lower element in the form of a major casting of bronze provided with a depending neck portion *a* internally screw-threaded to screw onto the 45 top of the burner stem *b*. This also screws over the thimble portion *c* of the priming trough *d*. This major casting is made up of a fire channel having a forwardly and upwardly inclined bottom. The rear of this 50 casting is formed into a suspended bridge *e* and connects with the rearwardly-extending nipple *f* and *g* that acts as a valve housing and fuel nozzle. This body is spaced from

the rear of the fire channel by the space *h* which is covered by the shield *x* with the air 55 ports *y*. This shield may be easily removed to clean the burner orifice simply by taking out the screw *z*. Along the top of the fire channel walls recesses *i* are moulded to form ports, some for supplying air for combustion and some to permit the spread of the flame outward to heat the channel walls for fuel preheating purposes, to be presently 60 described.

The cast iron triangular cover plate *j* is 65 clamped onto the top of the fire channel and the valve housing and nozzle body *g* by means of screws *k* and *l* respectively. This connects together the front and rear of the major casting and aids in strengthening the 70 bridge *e* between the front and rear ends of the major casting. Of course, it is possible to cast the cover as a part of the major casting but this is a somewhat expensive moulding operation, and furthermore, the cover 75 is kept very much cooler and will last very much longer by reason of being made a separate piece for it is desirable to make the major casting of bronze for easy machining and to secure a better heat-conducting 80 material to aid in generating the combustible gas. The cover, if made of bronze, would not stand up very long due to the excessive heat. Hence by making it a separate piece a better material for this purpose, to-wit, 85 cast iron, may be used. The division line between the cover and the major casting forms sufficient resistance for heat conduction to very materially keep down the heat.

Fuel oil (ordinarily gasoline) is forced up 90 through the stem *b* by air pressure supplied by the pump *m*. A vein *n* runs from the top of the burner stem back through the bridge *e*. The major casting is provided with a rib *o* internally projecting in the 95 channel so as to increase the exposure of the vein to the heat of the combustion chamber. This very materially aids in preheating the fuel oil. The fuel oil then passes through the vertical passage-way *q* to the 100 valve passage *r* and into the nozzle passage-way *s* that is controlled by the needle valve *t*. The purpose of the rib *u* is to provide material through which a vein may be drilled in case the burner is used in connection with 105 fire-pots. This, therefore, makes this form

of burner very much superior for both fire pots and torches, for as already explained, the burner may set directly on top of the stem when used as a torch burner.

5 Back of the fire channel are drilled a pair of drain holes 2 which allow the fuel oil to drip down into the priming trough *d* for starting. The fin *w* moulded on the back of the major casting prevents the oil from 10 dripping back on the casting and dropping off beyond the priming trough.

The cover is provided with downwardly-projecting ribs 3 which serve to locate the cover in proper registering position on the 15 fire channel.

The fire channel with its upwardly, forwardly inclined bottom serves to converge the flame to a narrow, thin flame and at the same time, by reason of the shape, to spread 20 the flame. The placing of a feeding vein on this inclined bottom brings it directly in the path of the mixture undergoing combustion to supply an adequate amount of heat to it to keep the burner from going 25 out in a cold wind. The bane of burners of this type is their going out when being used in exposed places due largely to cold blasts of air striking the fuel before it issues from the nozzle. By placing the vein in the position 30 indicated not only is a minimum of drilling required but the vein is in the very center of the burner and directly in the path of the mixture undergoing combustion.

What I claim is:

35 1. In a burner for the purpose specified, the combination of a lower element in the form of a casting including a body forming a valve housing, an oil nozzle, a nipple for receiving the valve stem, and a fan-like fire 40 channel with an upwardly-inclined floor; and an upper element in the form of a superposed cover removable for the channel, the said casting provided with a feeding vein and passage-ways leading to the nozzle.

45 2. In a burner of the type specified, the combination of a lower element in the form of a casting forming forwardly a fire channel of gradually lessening vertical cross section from back to front and forming 50 at the rear a valve housing, nozzle body, and a nipple for the valve stem; and a superposed removable cover for the fire channel, said casting provided with a feeding vein and passage-ways leading to the discharge 55 orifices of the nozzle.

60 3. In a burner of the type specified, the combination of a casting formed into a forward upwardly-opening shallow fire channel of progressively narrower vertical cross 65 section from back to front, a rearward body forming a valve housing and a nozzle and connected with the fire channel by a suspended bridge, and a rearwardly-extending nipple for the valve stem, and a cover secured over the fire channel.

4. In a burner of the type specified, the combination of a casting formed into a forward fire channel, a rearwardly-located body forming a valve housing and nozzle, and a rearwardly-extending nipple for the 70 valve stem, said body being connected with the forward channel by a suspended bridge forming a space forward of the nozzle; a ported shield covering said space; and a cover over the fire channel and also over 75 the body and reinforcing the said suspended bridge.

5. In a burner of the type specified, the combination of a casting forming a forward fire channel having an upwardly and forwardly-extending floor provided with a longitudinally-directed and medianly-located rib, said casting forming at the rear a valve housing and nozzle body provided with a rearwardly-extending nipple for the 80 valve stem, and said casting furthermore provided with a feeding vein through the said longitudinally-directed and medianly-located rib, and passage-ways connecting the feeding vein and the discharge orifices 85 of the nozzle, the said channel and body of the casting being connected by a suspended bridge through which runs also the rib and vein and forming above the bridge a space 90 between the body and the side walls of the 95 channel forward of the nozzle; a ported removable shield covering said space; and a cover supported over said fire channel.

6. In a burner of the type specified, the combination of a major casting provided 100 with a forwardly-located fire channel having an upwardly-inclined floor and a rearwardly-located body forming the valve housing and nozzle connected with the forwardly-located channel by a suspended bridge, 105 said casting having a feeding vein running through the suspended bridge and floor of the channel and a passage-way connecting the feeding vein with the discharge orifice in the nozzle; and a removable cover and 110 securing devices for securing the cover removably both to the channel and the rearwardly-located body, said body and the side walls of the fire channel being spaced forward of the nozzle.

115 7. In a burner of the character specified, the combination of a major casting provided with a forwardly-located fire channel and a rearwardly-located valve housing and nozzle body connected with the channel by 120 a suspended bridge, said major casting provided with a feeding vein, and passage-ways connected with the orifice in the discharge nozzle, and a removable cast iron cover clamped to both the fire channel and the top 125 of the valve housing and nozzle body, the said side walls of the channel being spaced forward from the valve housing body at the nozzle discharge orifice.

130 8. In a burner of the character specified,

the combination of a lower element in the form of a casting formed at its forward end with a fire channel having side walls with notches or recesses moulded into their upper edges as ports, and a removable cover clamped to the top of the said channel and over the said notches and thereby complet-

ing the walls of the notches, the said casting being provided with a feeding vein, a passage-way and a suitable valve housing and nozzle connected with the passage-way.

In testimony whereof I affix my signature.

FREDERICK L. LINDHORST.
